LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

INDICATING SYSTEM.

1,388,887.

Specification of Letters Patent. Patented Aug. 30, 1921.

Application filed November 1, 1919. Serial No. 334,922.

To all whom it may concern:

Be it known that I, LIPA POLINKOWSKY, a citizen of Russia, residing at Antwerp, Belgium, have invented certain new and useful Improvements in Indicating Systems, of which the following is a full, clear, concise, and exact description.

- This invention relates to telephone exchange systems and particularly to systems in which telephone circuits are extended by automatic switches to operators' positions, where the operators, by means of connecting apparatus at their disposal, complete the establishment of the connections.
- 15 The object of the invention is to provide an improved indicating device at the operators' positions for visually indicating to the operators the designations of lines with which connections are desired.
- 20 A feature of the invention relates to an indicating mechanism at an operator's position, in which a plurality of relays are arranged to be variably operated under the control of a register sender for selecting and 25 displaying a desired numerical designation upon visual indicating devices.

According to another feature of this invention a plurality of counting relays are arranged to be operated under the control 30 of the operation of the registers of a register sender, upon which a designation is registered, to select the proper numerical indicating devices for displaying the desired designation. By means of the arrangement 35 involving this feature the register sender, which controls in its operation the selection of the indicating devices, is also adapted to control selective switches for extending the connection to the position at which the indicator is located.

40 Such other features and advantages as are contemplated by the present invention will become apparent from the following description and the appended claims.

45 In the drawings which form a part of this specification there is shown in Figure 1 to the left of the broken line a portion of a cord circuit terminating in a first group selector, diagrammatically illustrated, and a 50 second group selector also represented diagrammatically. To the right of the broken line is shown the incoming end of a trunk line at a distant manual exchange terminating in a cord circuit at an operator's posi-

tion together with a subscriber's line belonging to the manual exchange.

Fig. 2 shows the detailed circuit and apparatus of a call indicating device located at the operator's position.

Fig. 3 shows circuits and apparatus of a register controlling mechanism in the first exchange which serves to control the operation of the selective switches and also the call indicating device in the manual exchange. For a study of the drawings the figures should be arranged as follows; Fig. 2 to the right of Fig. 1 and Fig. 3 below Fig. 1.

The present invention is applicable to systems wherein means are provided for extending subscribers' lines either to an operator's position in the exchange or directly to a register-controlling mechanism. In case a subscriber's line is automatically extended to a register-controlling mechanism upon the initiation of a call, an impulse transmitting device located at the calling substation may be utilized to position the registers of the controlling device in accordance with the digits of the desired number. These registers when positioned are thereafter operative to control the movement of selector switches to establish the desired connection. In case the calling exchange is of the semi-automatic type, where operators are employed to assist in the completion of connections, a calling line is usually extended first to the operator's position. The operator, upon receiving the desired designation from the calling subscriber, then proceeds to set the register-controlling mechanism either by means of a keyboard or an operator's impulse transmitter.

In the present arrangement, which has to do particularly with a system in which facilities are given for establishing connections between a semi-automatic or a full automatic exchange and a distant manual office, the register-controlling mechanism is arranged to control the operation of call indicator devices in addition to its selective switch controlling functions. If a calling subscriber in the automatic exchange illustrated to the left of Fig. 1 and in Fig. 3, wishes to obtain a connection with a subscriber's line in a distant manual office, such as shown to the right of Fig. 1, he first causes the register-controlling mechanism shown in Fig. 3

to be adjusted in accordance with the number of the desired line. Having thus been positioned, the register-controlling mechanism operates to first extend the calling line 5 to a trunk line leading to the desired manual office whereupon said controlling mechanism, continuing to operate, causes the display of the digits of the called line on a visual indicating device at the operator's 10 position.

The register-controlling mechanism comprises a plurality of sequence switch registers, one for each of the several digits, and each having ten different circuit controlling 15 positions. The particular type of controlling mechanism disclosed is designed to be variably positioned under the control of a stepping relay operated by series of impulses sent from a calling transmitter. A 20 sequence switch associated with the incoming circuits from the impulse transmitter serves to successively transfer the controlling stepping relay from one register to the next. When the registers have assumed 25 their set positions they then run through their remaining positions to successively control the desired selective operations. It will be understood that where it is desired to set the register mechanism by means of 30 an operator's keyboard a suitable wiring arrangement from the several rows of keys may be used instead of the stepping relay to determine the positioning of the registers. For a more detailed explanation of the 35 method of operation of the sequence switch registers and of the necessary construction of the calling transmitter for coöperation with the register-controlling mechanism, reference is made to an application filed by 40 Polinkowsky and Matthies, June 14, 1919, Serial No. 304,212.

A clearer understanding may be had of 45 this invention from a detailed description of the operation of the system in which it is embodied.

Assume that it is desired to extend a connection from the first exchange to a subscriber's line in the distant manual exchange. The calling subscriber upon initiating the 50 call has his line extended in any well-known manner to the cord circuit including repeating coil 90. In any well-known manner the calling subscriber's line is then extended over conductors 70 and 71 by means of a cord 55 finder sequence switch, contacts 72 and 73 to the windings of the stepping relay 325. The sequence switch which controls contacts 72 and 73, and which serves to associate an idle register mechanism with the cord circuit of the group selector, is not shown in detail. The operation of such sequence switch together with the detailed circuits and operations of the group selector switch whose brushes are shown at 93, 94 and 95 is explained in full in the above-mentioned ap- 60 65

plication, Serial No. 304,212, filed June 14, 1919. At the same time that the call is extended to the group selector and the circuits thereof are placed in condition for setting 70 of the register mechanism, a ground is placed on conductor 76 which causes the energization of the relay 323 over the following circuit: battery, right-hand winding of relay 323, contact 321 (1), conductor 393, contact 77 to the grounded conductor 76. 75

It may be noted at this time that the register mechanism is controlled by two sequence switches 320 and 350. All sequence switch contacts above and to the left of the uppermost broken line in Fig. 3 are controlled 80 by sequence switch 320, whereas sequence switch contacts below and to the right of said broken line are controlled by sequence switch 350. The contacts within the small rectangles at the bottom of the figure are 85 controlled by the respective registers 100, 110, 120, 130 and 140.

When, therefore, relay 323 energizes by means of a ground placed on the conductor 76 in the manner explained in the above-mentioned application, sequence switch 320 is driven from position 1 to position 3 by means of a circuit including contact 322 (1) and the left-hand winding of relay 323. Sequence switch 320 comes to rest in position 3 and at its contact 315 closes a circuit for the interrupter 316 in series with the primary winding of the dialing tone coil 317. As soon as relay 325 energizes in series 90 with conductors 70 and 71, and sequence switch 320 has reached position 3, a circuit is closed from ground, armature and back contact of relay 323, armature and front contact of relay 325, left-hand winding of differential relay 329, armature and back contact 95 of said relay, contact 330 (3) through the winding of register 100 to battery and ground. At the same time a parallel circuit is closed through the right-hand winding 100 of relay 329 to ground at the armature of relay 323. The relay 329, being differential, does not energize when a circuit is closed for both of its windings. Register 100, however, starts from position 0. Between positions 0 and 1 of register 100 the 105 local contact 103 is closed and the left-hand winding of relay 329 is shunted out, permitting said relay to energize. 110

The dialing tone, when impressed on conductors 311 and 312, signifies that the apparatus 120 is in condition to receive impulses. Upon the first interruption of the impulse circuit, relay 325 retracts its armature and opens the right-hand winding of relay 329, which relay thereupon deenergizes. As the 125 impulse circuit again closes, register 100 is energized once more and moves out of position 1. Relay 329 energizes, the register passes to position 2 and at the next interruption of the impulse circuit relay 329 be- 130

comes deenergized. This operation continues, the register 100 advancing from one position to another at each interruption of the impulse circuit until the impulse series 5 has been completed. At each retraction of the armature of relay 325 a momentary circuit is established from battery through the winding of relay 334, contact 318 (3), back contact and armature of relay 325 to ground 10 at the back contact and armature of relay 323. Relay 334, however, is made slow-to-energize and does not attract its armature during brief closures of its circuit. At the last interruption of the line, which, due to 15 the construction of the impulse sender, is made comparatively long, the circuit of relay 334 is closed for a sufficient interval to permit such relay to operate. A circuit is now completed from battery through the right-hand winding of relay 323 to ground at the armature of relay 334. Relay 323 energizes and closes a circuit through its left-hand winding and contact 322 to drive sequence switch 320 out of position 3. Before sequence switch 320 can reach position 6 the 20 impulse circuit is again closed and relay 334 deenergizes to in turn cause the deenergization of relay 323. Sequence switch 320, therefore, steps in position 6. 25 In position 6 of sequence switch 320 the stepping relay 325 in the incoming impulse circuit is operatively associated with a second number register 110. The vibration of the armature of said relay in response to 30 the second series of impulses causes, in a manner similar to that described, the setting of the register 110 up to a position corresponding to the number of impulses in such series. The method of setting the register 35 110 and the remaining successive registers 120, 130, 140 under the control of the stepping relay 325 will not be described in detail herein. For a full and specific description of the setting of these registers, reference is made to applicant's co-pending application filed June 14, 1919, Serial No. 304,212, wherein there is shown a register-controlling mechanism similar in all respects to the one disclosed in the present application. 40 As soon as the first register 100 has been positioned, sequence switch 320 advances into position 6. A circuit is then completed for driving sequence switch 350 into position 3. This circuit may be traced through the winding of sequence switch 350, contact 351 (1), contact 353 (6) to ground. In position 3 of sequence switch 350 the fundamental circuit for controlling the 45 brush selection of the first group selector shown in Fig. 1 is closed. This circuit may be traced from ground, contact 354 (3), contact and armature of relay 357 through the winding of stepping relay 355, conductor 50 396, contact 74, contact 78 through the wind- ing of relay 79 to battery and ground. In the well-known manner relay 79 closes a circuit for the brush tripping spindle power magnet (not shown) of the first group selector and brush selection takes place, stepping relay 355 in the fundamental circuit being short circuited for each brush tripping position passed over by the tripping spindle. Each time relay 355 deenergizes a 55 circuit is closed from ground over its armature and contact, contact 356, left-hand winding and armature and contact of differential relay 359, contact 342 (3), contact 102 through the winding of the register 100 to battery and ground. Hence, for each retraction of the armature of the relay 355, the register 100 advances one position. When register 100 reaches position 0, sequence switch 350 is driven into position 4 by means of a circuit including contact 341 (3), contact 102 (0), contact 343 (3), contact and armature and left-hand winding of relay 359, contact 356, and armature and relay 355. After brush selection has been completed at the first group selector, trunk 60 hunting follows and the selected set of brushes 93, 94 and 95 are driven to the terminals 60, 61 and 62 of an idle trunk leading to a second group selector 63, 64, 65. When the second register 110 has been 65 positioned and sequence switch 320 passes into position 8, the sequence switch 350 is driven from position 4 into position 6. The circuit for moving said sequence switch out of position 4 includes the contact 351 (4) 70 and contact 353 (8). In position 6 of sequence switch 350 the fundamental circuit is closed through to the second group selector, and brush selection takes place under the control of the thousands register 110 in the manner described in the above-mentioned application, Serial No. 304,212, filed June 14, 1919. At the end of brush selection of the second group selector, trunk 75 hunting ensues and the brushes 63, 64 and 65 are driven into engagement with the terminals 66, 67, 68 of an idle trunk 411, 412, leading to the distant manual exchange. Sequence switch 350 at the end of brush selection at the second group selector is also 80 driven from position 6 into position 7 by means of a circuit from battery through the winding of sequence switch 350, contact 341 (6), contact 102 (0), contact 342 (6), contact 111 (0), contact 343 (6), contact and 85 armature and left-hand winding of relay 359, contact 356 to ground at the contact and armature of relay 355. The connection having thus been extended through to the distant manual exchange, the 90 sequence switch (not shown) of the first group selector circuits is now advanced to a position to extend the fundamental circuit from the register-controlling mechanism over its contacts 91 and 92 to the distant exchange. 130

of relays 436, 447 and 448 to battery at the contact and armature of relay 439. In a parallel circuit relays 437 and 438 are also energized. The circuits are now prepared for operating the counting relays of the number indicating device under the control of the hundreds register 120 in the calling exchange to select the desired number lamp in the hundreds row. The counting relays are arranged in pairs such as 469 and 479, 460 and 470, 461 and 471 and so on up to the last pair 468 and 478. 70 75

The manual exchange in the present system is assumed to have a capacity of 2,000 lines, an even and an odd thousand as, for example, the zero thousand and the first thousand. Accordingly, only two thousands lamps are required, lamp 510 for the zero or even thousand and lamp 511 for the first or odd thousand. As will be more clearly explained hereinafter, the selection of the proper thousands lamp is determined by the setting of the thousands register 110 which controls the operation of the second group selector in the calling exchange. The hundreds lamps are associated with each other in pairs, each pair comprising an even hundreds lamp and the next succeeding odd hundreds lamp as, for instance, the zero and first hundreds lamps 520 and 521. The selection of the proper pair of hundreds lamps is accomplished by the counting relay set and the selection of the even or odd hundreds lamp in the pair is determined by the setting of the hundreds register 120, as will be later explained.

When, therefore, a fundamental circuit is completed, as above described, and relays 436, 447, 448, 437 and 438 are energized, a circuit is closed to ground as follows: Battery, winding of relay 452, back contact and left-hand armature of relay 434 and the contact and armature of relay 438. This direct circuit to ground over relay 452 shunts out the stepping relay 355 at the register-controlling mechanism. Relay 355 de-energizes and closes a circuit from ground over its armature and contact, contact 356, left-hand winding and armature and contact of relay 359, contact 345 (9), contact 121 through the winding of register 120 to battery. In the well-known manner register 120 advances one step toward its normal position. Relay 437 which energizes simultaneously with relay 438 closes a circuit from ground over its armature and contact, left-hand armature and back contact of relay 441, right-hand armature and back contact of relay 469 through the upper counting relay 479, normally closed contact of relay 442, front contact and armature of relay 447 to battery to ground. Relay 479 energizes and prepares a circuit for the lower counting relay 469 which extends over the left-hand armature and contact of relay 130

479 to ground at the normally closed contact of relay 443. Relay 469, however, is not energized so long as its winding is shunted out by the direct circuit to ground 5 at the contact and armature of relay 437. Relay 448 is constructed to attract its armature slowly. As soon as relay 448 closes its front contact, relay 439 is energized and attracts its armature to open the circuit of 10 relays 436, 447, 448, 437 and 438. Relay 438 immediately releases its armature, removes the shunt from around stepping relay 355 which relay again energizes. When relay 437 retracts its armature, the lower 15 counting relay 469 becomes energized in series with relay 479. Relay 448 immediately releases its armature and opens the circuit of slow-to-release relay 439, which, after an interval again closes the above traced circuit 20 for relays 436, 447, 448, 437 and 438. Relays 436 and 447 are made sufficiently sluggish so as not to release their armatures during the time the armature of relay 439 is attracted. Hence the first pair of counting 25 relays 469 and 479 remains locked up over the left-hand armature and front contact of relay 447. Immediately that relay 438 again attracts its armature the stepping relay 355 at the register-controlling 30 mechanism is shunted and hundreds register 120 advances to the next position. Relay 437, energizing, closes a circuit from ground over its armature and contact, left-hand armature and back contact of relay 35 441, right-hand armature and front contact of relay 469, right-hand armature and back contact of relay 460 through the lamp 551, winding of relay 470, normally closed contact of relay 442 to battery at the front contact 40 and armature of relay 447. Relay 470 energizes and prepares a circuit for the lower counting relay 460. As soon as relay 439 is energized, as above described, and relay 438 de-energizes, the stepping relay 355 again attracts its armature. Relay 437 de-energizing at the same time removes the shunt from around the winding of relay 460, and this relay energizes in series with relay 470 to ground at the normally closed 50 contact of relay 443. This procedure continues, a pair of counting relays being energized and locked up for each position through which the hundreds register 120 is driven. When register 120 reaches position 55 0, a circuit is closed from battery through the winding of sequence switch 350, contact 341 (9), contact 102 (0), contact 342 (9), contact 111 (0), contact 343 (9), contact 121 (0), contact 345 (9), contact and armature 60 and left-hand winding of relay 359, contact 356 to ground at the contact and armature of relay 355. In a circuit parallel to the one just traced, relay 357 is also energized. Relay 357 opens the fundamental circuit while 65 sequence switch 350 moves from position 9 into position 10. As soon as relay 438 de-energizes after the fundamental circuit has been opened by relay 357, relay 452 releases its armature. With relay 452 de-energized, and relay 436 still maintaining its armature attracted a circuit is closed from battery through the winding of relay 444, back contact and armature of relay 445, front contact and armature of relay 436, back contact and armature of relay 452, armature and 70 contact of relay 435 to ground at the front contact and armature of relay 431. At the same time a circuit is closed for one of the lamp-selecting relays, such as 480 and 481. Assume, for example, that the thousands digit is even and that only the first two counting relays 469 and 479 were energized under the control of the hundreds register 120. In this case the lamp-selecting relay, such as 480 is the one energized and 75 its circuit may be traced from battery to the winding of said relay, back contact and left-hand armature of relay 460, left-hand armature and front contact of relay 469, back contact and armature of relay 444, and thence to ground in parallel with the circuit above traced for relay 444. Relay 444 is made slow-to-energize so that relay 480 is given sufficient time to attract its armature before its energizing circuit can be opened 80 at the back contact of relay 444. Relay 480 energizes and locks up in a circuit over its contact and armature, through the zero thousands lamp 510, to ground at the front contact and armature of relay 431. Relay 85 444, after an interval, attracts its armature and closes a circuit from battery through its winding, armature and front contact, through the winding of relay 445 to ground 90 at the front contact and armature of relay 431. Relay 445 does not energize, however, at this time, since its winding is short-circuited over the circuit above traced 95 through the front contact and armature of slow-to-release relay 436. When, after an interval, relay 436 retracts its armature, relay 445 becomes energized in series with relay 444. Relay 447 also slow-to-de-energize 100 is arranged to release its armature slightly before the release of relay 436. When relay 447 de-energizes it opens at its front contact the locking circuit which, up to this time, has been maintaining the counting relays 105 energized.

Upon sequence switch 350 coming into 120 position 10 after register 120 reaches position 0, the following circuit is closed to drive said sequence switch into position 11: battery through the winding of sequence switch 350, contact 351 (10), contact 353 to 125 ground. In position 11 of sequence switch 350 the fundamental circuit is again closed at contact 358 and relays 355 and 452 attract their armatures ready for controlling the selection of the tens number lamps in ac- 130

cordance with the positioning of tens register 130. When relay 452 energizes it closes the above described circuits to cause the energization of relays 436, 447, 448, 437 and 438. Relay 437 closes a circuit from ground over its armature and contact, left-hand armature and back contact of relay 441, right-hand armature and back contact of relay 469 through the winding of the upper counting relay 479, normally closed left-hand contact of relay 442 to battery and ground at the front contact and armature of relay 447. Relay 479 prepares a circuit for relay 469, which becomes energized, as described, when relay 437 retracts its armature. Relay 438 energizes and shunts out the stepping relay 355 in the fundamental circuit. Relay 355 closes a circuit from ground over its armature and contact, contact 356, left-hand winding and armature and contact of relay 359, contact 346 (11), contact 131 through the winding of tens register 130 to battery. Register 130, as is well understood, advances one step from the position in which it is standing. When relay 439 operates to open the circuit of relays 436, 447, 448, 437 and 438, relays 469 and 479 lock up in series with each other to ground at the normally closed contact of relay 443. Relay 438, deenergizing, removes the shunt from around stepping relay 355 which thereupon attracts its armature. When relay 439 deenergizes to again close the circuit of relays 437 and 438, the upper counting relay 470 of the second pair is energized, relay 438 shunts out the stepping relay 355 and the register 130 advances through another position. This operation continues, one pair of counting relays being energized and locked up for each position to which the register 130 advances until said register has been restored to its 0 position. In position 0 of the register 130, relay 357 and sequence switch 350 are energized in parallel circuits leading over contact 347 (11), contact 131 (0), contact 346 (11), contact and armature and left-hand winding of relay 359, contact 356 to ground at the armature and contact of relay 355. Relay 357 opens the fundamental circuit whereas sequence switch 350 moves out of position 11 and into position 12. As soon after the fundamental circuit has been opened at the register-controlling mechanism as relay 438 releases its armature, relay 452 becomes deenergized. With relay 452 deenergized and the slow-operating relay 436 maintaining its armature attracted, a circuit is closed from ground, armature and front contact of relay 431, contact and armature of relay 435, armature and back contact of relay 452, armature and front contact of relay 436, armature and front contact of relay 445, right-hand armature and back contact of relay 442 through the winding of relay 446 to battery. At the

same time a circuit is closed for the particular tens number lamp relay which has been selected by the counting relay set. Assuming that relay 492 is the one selected, its circuit may be traced from battery through the winding of said relay, back contact and right-hand armature of counting relay 478, front contact and right-hand armature of relay 464, through the front contacts and right-hand armatures of the upper counting relays preceding relay 464, back contact and right-hand armature of relay 446 and thence to ground over the circuit above traced for relay 446. Relay 446 is constructed so as to attract its armature slowly, and therefore does not energize to open the circuit of relay 492 until after said latter relay has had time to attract its armature. Relay 492, when energized, locks up over its contact and armature to ground at the front contact and armature of relay 431. Relay 446 at its right-hand armature closes a circuit in series with relay 442 to ground at the front contact and armature of relay 431. Relay 442, which remains shunted as long as relay 436 is retaining its armature, operates in series with relay 446 as soon as relay 436 deenergizes. Relay 447, which releases its armature slightly prior to the deenergization of relay 436 opens the locking circuit of the counting relays before relay 442 has time to energize and attract its left-hand armature. Sequence switch 350 at the register-controlling mechanism, on reaching position 12, is advanced into position 14 as soon as sequence switch 320 has reached position 15. The circuit for sequence switch 350 will be traced from battery to the winding of said sequence switch, contact 341 (12) to ground at the contact 331 (15). In position 14 of sequence switch 350, the fundamental circuit is again closed at contact 358 and relays 355 and 452 energize ready for the selection of the units number lamp of the call indicator mechanism under the control of the units register 140. Relay 452 again closes the circuit of relays 437 and 438, causing the energization of the first counting relay 479 and the short-circuiting of the stepping relay 355 in the fundamental circuit. Relay 355 closes a circuit from ground over its armature and contact, contact 356, left-hand winding and armature and contact of relay 359, contact 346 (14), contact 141 through the winding of the units register 140 to battery. Register 140 advances through one position and upon the release of relay 438 stepping relay 355 is energized. When relay 437 releases its armature, the shunt is removed from around the lower counting relay 469 which relay thereupon locks up in series with relay 479. The holding circuit for the counting relays may now be traced from battery over the left-hand armature and front contact of relay 442, through the

windings of relays 479 and 469 in series, contact and armature of relay 479 to ground at the normally closed contact of relay 443.

On the next energization and deenergization 5 of relays 437 and 438, the second set of counting relays 470 and 460 are energized and locked up, stepping relay 355 is operated and register 140 is driven to another position. This operation continues until

10 register 140 reaches position 0, at which time parallel circuits are closed for relay 357 and sequence switch 350. These circuits include contact 347 (14), contact 142 (0), back contact and armature of relay 374, 15 contact 141 (0), contact 346 (14), contact and armature and left-hand winding of relay 359, contact 356 to ground at the contact and armature of relay 355. Relay 357 opens the fundamental circuit while sequence 20 switch 350 advances from position 14 into position 16. As soon after the fundamental circuit is opened at relay 357 as relay 438 deenergizes, relay 452 releases its armature.

A circuit is thereupon closed from battery 25 to the left-hand winding of relay 434, front contact and right-hand armature of relay 442, front contact and armature of relay 445, front contact and armature of relay 436, back contact and armature of relay 452, 30 armature and contact of relay 435 to ground at the front contact and armature of relay 431. Relay 434, at its left-hand armature, opens the circuit of relay 452 to prevent the further energization of this relay. At its 35 right-hand armature relay 434 closes circuits from battery through the windings of relays 455 and 456, right-hand winding, front contact and armature of relay 434 to ground at the front contact and armature of relay 40 431.

Relays 455 and 456 prepare circuits for the selected hundreds, tens and units number indicating lamps. The circuit of the hundreds lamp may be traced from battery, 45 right-hand armature and front contact of relay 480, through the even or zero hundreds lamp 520, back contact and right-hand armature of relay 449 to ground at the contact and right-hand armature of relay 456. The 50 circuit for the selected tens lamp may be traced from battery, left-hand armature and front contact of relay 492 through the No. 8 tens lamp 581 to ground at the contact and outer left-hand armature of relay 456. The 55 circuit of the selected units lamp as, for instance lamp 541, is traceable from ground, left-hand armature and contact of relay 455, left-hand armature and back contacts of relay 441, right-hand armatures and front 60 contacts of relays 469 and 460, right-hand armature and back contact of relay 461 through the units lamp 541, winding of relay 471 to battery through the front contact and left-hand armature of relay 442.

65 After the units register 140 has com-

pleted its controlling functions, the register-controlling mechanism is restored to normal and the controlling sequence switch of the first group selector is driven into its talking position in the manner described in 70 the above-mentioned application, Serial No. 304,212, filed June 14, 1919. With the sequence switch contacts 91 and 92 in their talking position, such as position 9, the trunk circuit 411 and 412 is extended through to 75 the repeating coil 90. Relay 435 is now energized in a circuit from ground through the winding of said relay, front contact and left-hand armature of relay 434, conductor 592, front contact and left-hand armature 80 of relay 417, trunk conductor 412, terminal 67, brush 64, terminal 61, brush 94, contact 92, supervisory relay 87, through the lower right-hand winding of repeating coil 90 to battery and ground. The purpose of relay 85 435 which energizes at this time will be described in detail hereinafter.

When relay 455 energizes the following circuit is also closed to cause the lamp 410 at the operator's position to flash, indicating 90 that a call is awaiting attention upon the call indicator: ground, interrupter 461, right-hand armature and contact of relay 455, back contact and right-hand armature of relay 432, conductor 593, front contact and 95 right-hand armature of relay 417 through the lamp 410, back contact and armature of relay 413 to battery and ground. The operator's attention being attracted by the flashing of lamp 410 observes the designation displayed upon the call indicator lamps and seizing plug 421 of the trunk 411, 412 inserts it in the jack 420 of the called line 400. Relay 422 is thereby energized in a circuit over the sleeve of the plug 421 and cut- 100 off relay 427. At the left-hand contact of relay 422, parallel circuits are closed for the energization of relays 415, 423 and 428. The circuit of relay 428 extends from battery through the lower right-hand winding of re- 105 peating coil 416, winding of relay 428, armature and back contact of relay 424 to ground at the left-hand armature and contact of relay 422. The circuit of relay 423 extends over the back contact and armature of relay 429 to ground at the left-hand armature of relay 422. Relay 415 opens the circuit through the right-hand low resistance winding of relay 419, and relay 417 being unable 110 to remain energized in series with the left- 115 hand high resistance winding of relay 419 releases its armatures. Trunk circuit 411, 412 is now connected through the left-hand windings of repeating coil 416. The relay 428 short-circuits the high resistance winding of 120 relay 413 permitting the energization of supervisory relay 87 in the calling exchange. When relay 415 energizes it closes a circuit 125 from battery over its left-hand armature and front contact, through the winding of slow- 130

to-release relay 424 to ground through the cut-off relay 427. Relay 424 attracting its armature opens the circuit of relay 428 which in turn removes the shunt from around the 5 high resistance winding of relay 413. Supervisory relay 87 in the calling exchange is now deenergized and may serve in any well-known manner to move the sequence switch into an advanced position and display a 10 ringing signal. Relay 415 also closes a circuit from battery over its left-hand armature and front contact through the left-hand winding of relay 418, right-hand armature and back contact of relay 417 to ground at 15 the left-hand armature and contact of relay 422. Relay 418 energizes and locks up in a circuit from ground over its right-hand armature and front contact and right-hand winding to battery at the front contact and 20 armature of relay 413. Relay 418, at its left-hand armature, opens the circuit through the high resistance winding of relay 419, and relays 419 and 431 become deenergized. The release of relay 431 opens the holding circuits 25 of relays 444, 445, 446 and 442. These relays deenergize causing the release of the call indicator mechanism.

When relay 423 attracts its armatures it 30 closes a circuit for the application of ringing current to the called line. This circuit extends from the ringing source 463 through the right-hand winding of relay 429, front contact and right-hand armature of relay 423, tip of the plug 421 and jack 420 over 35 the loop of the line 400, ring of jack 420 and plug 421, right-hand armature and front contact of relay 422 to ground at the left-hand armature and front contact of relay 423. As soon as the called subscriber 40 responds, relay 429 energizes and locks up in a circuit over its left-hand winding to ground at the left-hand armature of relay 422. Relay 429 opens the circuit of relay 423 which, by releasing its armatures, completes the 45 talking circuit from the right-hand windings of the repeating coil 416 through to the called line 400.

At the termination of conversation the operator removing plug 421 from jack 420 50 causes the deenergization of relays 422 and 424. Relay 422 opens the holding circuits of relays 415 and 429 so that these relays now release their armatures. When the called line supervisory relay 428 deenergizes 55 as the called subscriber hangs up his receiver, the supervisory relay 87 in the calling exchange is also deenergized and may operate to either display a disconnect signal before an operator or initiate the automatic 60 release of the switching mechanism in said exchange.

If the called line 400 is busy the operator, after having tested the jack 420, then inserts the plug 421 into a busy jack 430. Relay 65 422 energizes in series with the resistance

425 and closes a circuit for the energization of relay 415 as described. The relay 424, however, being marginal, does not energize in parallel with relay 422 in a circuit including the resistance 425. Therefore, the relay 428 remains permanently energized and short-circuiting the right-hand winding of relay 413 permits the energization of supervisory relay 87 in the calling exchange. Relay 87 by remaining energized may cause in 75 any suitable manner the continued display of a supervisory signal to indicate to an operator that the called line is busy.

It will next be considered that the called line in the manual exchange belongs to the 80 second or odd thousand. In other words, the thousands digit of the line will be 1. Furthermore, it will be assumed that the second or hundreds digit of the called line is odd as, for example the digit 1, next succeeding the digit 0. It will be remembered that the hundreds digit of the line 400 previously described was taken as 0, the zero hundreds lamp 520 being lighted, and that the next succeeding odd hundreds digit lamp 90 521 is the one which mates with lamp 520.

As is well understood, the grouping of trunks and lines at the switches of the character used in this system is arranged on the basis which does not correspond with the basis of decimal numbers. Accordingly, the register-controlling mechanism must be designed so as to control the operation of the switches in the selection of trunks and lines, arranged on some arbitrary basis, so that 100 the final selection of the line may be made in accordance with a designation based on the decimal system. To this end the register-controlling mechanism is capable of performing certain translations when either 105 the thousands digit or the hundreds digit is odd. If the thousands digit is odd, the thousands register 110, as will be explained hereinafter, is made to step to its ninth position, which means that the group selector under 110 its control is directed to the same level of trunks to which it would have been directed had the thousands digit been the next lower even digit. When later during the hundreds selection operation the hundreds register 115 100 has reached its position 0, the thousands register 110 is then driven from position 9 to position 0, and this additional step is made to control the hundreds group selector so that an additional step is taken and the 120 connection extended over a group of trunks leading to the proper odd thousand. If the hundreds digit is odd then the units register 140 is designed to make a complete additional revolution which drives the selected 125 set of brushes of the final selector over the first or even hundreds section of the terminal bank on to the terminals of the called line in the second or odd hundreds section of the terminal bank.

When, therefore, the register-controlling mechanism has been positioned and the calling line is extended over a trunk to a call indicator at a manual exchange, the mechanism of such indicator must be capable of retranslating the setting of the register-controlling mechanism in order that the designation displayed on the indicator lamps shall correspond with the decimal designation 10 originally registered on the controlling mechanism.

Since, in the case now under consideration, the thousands and hundreds digit of the called line in the manual office are each odd, 15 both being the digit 1, registers 110 and 120 are driven to their complementary positions 9. With register 110 in position 9, relay 360 is energized during the time sequence switch 350 is passing through position 5. The circuit of relay 360 is traceable from battery through the winding of said relay, contact 112 (1) to ground at contact 340. Relay 360 locks up in a circuit over its left-hand armature to ground at 20 contact 361 (6). When brush selection takes place at the selector 63, 64, 65, and the fundamental circuit is closed at contact 358 in position 6 of sequence switch 350, relay 355 becomes energized. The trip spindle in the 25 well-known manner advances toward the first brush-tripping position where it shorts-circuits the stepping relay 355. Relay 355 deenergizes and closes a circuit from ground over its armature and contact, contact 356, 30 left-hand winding and armature and contact of relay 359, contact 343 (6), contact 111 (9), right-hand armature and front contact of relay 360, contact 113 (9), contact 342 (6), contact 102 (0), contact 341 (6), 35 through the windings of sequence switch 350 and relay 357 in parallel to battery. Sequence switch 350 goes into position 7 while relay 357 opens the fundamental circuit. Hence, as the tripping spindle reaches the 40 first brush-tripping position, the fundamental circuit is opened in the well-known manner at the group selector and brush selection ceases. This means that the first level of trunks leading to the manual exchange 45 has been selected, the thousands digit being 1, and the register 110 remains in position 9. The same level of trunks is selected when the thousands digit is the next lower even digit, the register 110 being, in this case, 50 in position 0.

Circuits at the manual exchange are now prepared as hereinbefore described in detail for the selection of the hundred indicator lamp. Sequence switch 350 goes into position 55 9 and the fundamental circuit is extended through to the indicator mechanism including relay 452. Register 120 first advances from position 9 into position 0 to send one impulse which results in the energization and locking up of the first pair of

counting relays 479 and 469. With register 120 in position 0, the thousands register is next restored from position 9 to position 0 by means of the following circuit: battery, through the winding of register 110, back 70 contact and right-hand armature of relay 360, contact 111 (9), contact 343 (9), contact 121 (9), contact 345 (9), contact and armature and left-hand winding of relay 359, contact 356 to ground at the armature of relay 75 355. It will be observed that relay 360, which was locked up over its left-hand armature deenergizes as soon as sequence switch 350 passes out of position 6 to open contact 361. Register 110 in passing from position 9 to 80 position 0 sends an impulse over the fundamental circuit in addition to the impulse sent by the hundreds register, and consequently the second pair of counting relays 470 and 460 are energized and locked up. 85 With register 120 in position 0, sequence switch 350 is now driven from position 9 into position 11 to control the tens selection. The circuit for driving sequence switch 350 into position 11 extends from 90 battery through the winding of said sequence switch, contact 341 (9), contact 102 (0), contact 342 (9), contact 111 (0), contact 343 (9), contact 121 (0), contact 345 (9), contact and armature and left-hand winding 95 of relay 359, contact 356 to ground at the armature and contact of relay 355. Since two pairs of counting relays are locked up at the indicator mechanism the second relay 481 is energized instead of the first relay 100 480 when relay 452 releases its armature. The circuit for relay 481 extends from ground, armature and front contact of relay 431, contact and armature of relay 435, armature and back contact of relay 452, armature 105 and front contact of relay 436, armature and back contact of relays 445 and 444, contact and left-hand armatures of relays 469 and 460, left-hand armature and back contact of relay 461 through the winding of relay 481 110 to battery. Relay 481 energizes and locks up in a circuit over its left-hand contact and armature through the odd thousands lamp 511 to ground at the front contact and armature of relay 431.

On passing through position 8, sequence switch 350 at its contact 344 closes a circuit for relays 373 and 374. This circuit leads from battery through the windings of these relays, contact 344 (8) to ground at contact 122 of the hundreds register, which is closed in position 9. Relays 374 and 373 lock up in a circuit over the armature and contact of relay 373, contact 143 closed in positions 1 to 9 to ground at contact 352. 120 After the tens digit lamp has been selected and the fundamental circuit is again closed to perform the selection of the units lamp under the control of the units register 140, relays 355 and 452 become energized. As 130

hereinbefore explained, sequence switch 350 is now standing in position 14. The units register 140 restores to its 0 position, a pair of counting relays being energized and 5 locked up for each of the successive positions passed over by said register. Since the hundreds digit is odd the units register instead of coming to rest in position 0, as in the case of an even hundreds digit, passes 10 through a complete additional cycle of operation. The circuit for driving register 140 out of position 0 may be traced from battery through the winding of said register, front contact and armature of relay 374, 15 contact 141 (0), contact 346 (14), and thence to ground at the armature and contact of relay 355. As a result of the register 140 making this additional cycle of operation, the entire set of counting relays are 20 energized and locked up. When the last pair of counting relays 468, 479 energize a circuit is closed from ground, armature and contact of relay 437, left-hand armature and back contact of relay 441, right-hand armatures and front contacts of all of the lower 25 counting relays, right-hand armature and back contact of relay 441 through the winding of relay 443 to battery at the front contact and armature of relay 447. Relay 443 energizes, and at its left-hand contact opens 30 the locking circuit of the counting relays. Relay 443 also closes a circuit in series with itself for the left-hand winding of relay 433. As soon as relay 437 deenergizes to 35 move the shunt from around the left-hand winding of relay 433, this relay operates and closes the following circuit: ground, armature and front contact of relay 433, through the right-hand winding of said relay 40 through the windings of relays 441 and 449 in parallel and thence to battery at the left-hand armature and front contact of relay 442. Relay 443 again deenergizes, its circuit being opened at the right-hand back 45 contact of relay 441. At the left-hand armature of relay 441, the circuit leading from the contact of relay 437 is shifted from the right-hand armature of relay 469 to the right-hand armature of the second counting 50 relay 460. When relay 437 energizes again, the units register 140 continuing to rotate, the second pair of counting relays 460 and 470 are energized and locked up. As the units register 140 reaches position 0 the second 55 time, a number of pairs of counting relays corresponding to the units digit, as registered on the register 140, has been energized and locked up so that the proper units lamp is selected. Sequence switch 350 is 60 now driven into position 17 by means of a circuit from battery, through the winding of said sequence switch, contact 341 (16), contact 102 (0), contact 342 (16), contact 111 (0), contact 343 (16), contact 121 (0),

contact 345 (16), and thence to ground at 65 the contact and armature of relay 355.

Since the relay 449 at the indicator mechanism is energized in series with relay 433, a circuit is closed for the odd hundreds lamp 521 instead of for the even hundreds lamp 70 520. This circuit extends from battery over the right-hand armature and contact of relay 481 through the lamp 521, front contact and right-hand armature of relay 449 to ground at the right-hand armature of relay 75 456. Had the hundreds digit been even as, for instance, the digit 0 and the thousands digit odd, relay 481 would have been energized as explained, and since relay 449, in this case, remains deenergized a circuit for 80 the zero lamp 520 is completed at the right-hand armature of relay 481.

The relays 432, 454 and 453 in Fig. 2 are adapted to control restoration of the indicating mechanism in the event of a premature release by the calling subscriber. When relay 431 first becomes energized a circuit is closed for the left-hand winding of relay 454 including the back contact and right-hand armature of relay 434 and the front 90 contact and armature of relay 431. When each of the controlling registers has been restored to normal at the end of the successive impulse series, relay 452 deenergizes and a short time later relay 436 releases its 95 armature. A circuit is then closed from battery to the left-hand winding of release relay 432, contact and armature of relay 454, back contacts and armatures of relays 436, 452 and 435 to ground at the front contact and armature of relay 431. This circuit is only closed for a brief period when the everchanging operation takes place at the register-controlling mechanism. The release relay 432 being of the slow-to-operate 100 character does not have sufficient time to attract its armatures while relays 436 and 452 are simultaneously deenergized. Should the call be abandoned before all of the calling 105 registers have been set or should for any other reason the fundamental circuit be maintained opened at the register set longer than the normal period required for transition from one controlling operation to the next, relay 432 attracts its armatures. At 110 the left-hand armature of relay 432, circuit of relay 431 is opened, and this relay, by deenergizing, causes the restoration of the indicating mechanism.

After the completion of the selection of 115 the units digit lamp, it will be recalled that relay 434 energizes. At its right-hand armature and back contact this relay opens the above-traced circuit for the left-hand winding of relay 454. In the normal operation of the system, relay 435 energizes as 120 hereinbefore described in the circuit leading to battery and ground at the repeating 125

coil 90 in the distant exchange. If release take place in the calling exchange at this time, relay 435 fails to energize when relay 434 attracts its left-hand armature and the following circuit is closed: battery, through the winding of relay 453, back contacts and armatures of relays 436, 452 and 435 to ground at the front contact and armature of relay 431. Relay 453, which is slow to energize, attracts its armature after an interval and closes a circuit for the right-hand winding of relay 454. Relay 454 energizes and the above-traced circuit of the release relay 432 is completed to cause the restoration of the indicating mechanism.

What is claimed is:

1. In a telephone system, selective switches for extending telephone connections, a controlling mechanism comprising a plurality of registers, means for positioning said registers, means for operating certain of said positioned registers for controlling the operation of said switches, a plurality of indicating devices, a series of relays, means for operating the remaining positioned registers of said mechanism, means controlled by the operation of such registers for operating the relays of said series, and means under the control of said relays for variably selecting said indicating devices.
2. In a telephone system, selective switches for extending telephone connections, a controlling mechanism comprising a plurality of registers, means for variably positioning said registers in accordance with desired designations, means for operating certain of said positioned registers for controlling the operation of said switches, a plurality of indicating devices, a series of relays, means for operating the remaining positioned registers of said mechanism, means controlled by the operation of such registers for operating the relays of said series, and means under the control of said relays for variably selecting said indicating devices.
3. In a telephone system, an operator's position, selective switches for extending telephone connections to said position, a controlling mechanism comprising a plurality of registers, means for variably positioning said registers, means for restoring to normal certain of said registers to control the operation of said switches, a plurality of number indicating devices at the operator's position, a series of relays, means for restoring to normal the remaining registers of said mechanism, means controlled by the restoration of such registers for operating the relays of said series, and means under the control of said relays for variably selecting said indicating devices.
4. In a telephone system, an operator's position, selective switches for extending telephone connections to said position, a con-

trolling mechanism comprising a plurality of sequence switch registers, means for variably positioning said registers in accordance with the designations of called lines, means for restoring to normal certain of said registers to control the operation of said switches, a plurality of number indicating devices at the operator's position, a series of relays, means for restoring to normal the remaining registers of said mechanism, means controlled by the restoration of such registers for operating the relays of said series, and means under the control of said relays for variably selecting said indicating devices.

5. In a telephone system, selective switches for extending telephone connections, a controlling mechanism comprising a plurality of registers, means for positioning said registers, means for operating certain of said positioned registers to control the operation of said switches, a plurality of number indicating devices, a series of relays, means for operating the remaining positioned registers of said mechanism, means controlled by the operation of such registers for variably operating the relays of said series, and means dependent upon the number of relays operated for selecting the desired indicating devices.

6. In a telephone system, selective switches for extending telephone connections, a controlling mechanism comprising a plurality of registers, means for positioning said registers, means for operating certain of said positioned registers to control the operation of said switches, a plurality of number indicating lamps, a series of counting relays, means for operating the remaining positioned registers of said mechanism, means controlled by the operation of such registers for variably operating said counting relays, and means dependent upon the number of relays operated for selecting the desired indicating lamps.

7. In a telephone system, an operator's position, selective switches for extending talking connections to said position, a controlling mechanism comprising a plurality of registers, means for positioning said registers, means for operating certain of said positioned registers to control the operation of said switches, a plurality of number indicating devices at the operator's position, a set of counting relays, means for operating the remaining of said positioned registers, means controlled by the operation of such registers for operating in succession the relays of said set, and means dependent on the number of counting relays operated for variably selecting said indicating devices.

8. In a telephone system, selective switches for extending talking connections, a controlling mechanism comprising a plurality of

- registers, means for variably positioning said registers, means for operating certain of said positioned registers to control the operation of said switches, a plurality of 5 groups of number indicating devices, a set of counting relays, means for operating in succession the remaining of said positioned registers, means controlled by each register in its operation for operating said counting 10 relays, and means dependent on the number of relays operated for variably selecting a number indicating device in each of said groups.
9. In a telephone system, selective switches 15 for extending talking connections, a controlling mechanism comprising a plurality of registers, means for variably positioning

said registers, means for restoring to normal certain of said positioned registers to control the operation of said switches, a plurality of groups of number indicating devices, a set of counting relays, means for restoring to normal in succession the remaining of said positioned registers, means controlled by each register in its restoration for 20 operating said counting relays, and means dependent on the number of relays operated for variably selecting a number indicating device in each of said groups. 25

In witness whereof, I hereunto subscribe 30 my name this 11th day of October, A. D. 1919.

LIPA POLINKOWSKY.
